UNITED STATES PATENT OFFICE.

CHAUNCEY MARSH GOODRICH, OF WINDSOR, ONTARIO, CANADA.

OVERHEAD SUPPORT.

Application filed January 5, 1926. Serial No. 79,362.

This invention relates to supports for the overhead systems of electric railways, and more particularly to an improved form of insulator pin support and mounting for such

5 supports, and has for its object the provision of such a support providing for an adjustable mounting of the insulator pin.

Another object is to provide a mounting for the insulator pin of supports of this 10 class which in itself will provide an insulating support for the messenger or supporting cable should such cable become loosened from the insulator pin or the pin should break.

15 A further object is to provide a mounting for the insulator pin which may be adjusted horizontally on the support within predetermined limits.

A still further object is to provide a support of the class described having the novel 20 design, construction and combination of parts hereinafter described and illustrated in the accompanying drawings.

In the drawings:

25 Figure 1 is an elevation of a supporting structure embodying my invention.

Figure 2 is a transverse sectional view through the truss or girder showing the insulator pin mounting.

30 Figure 3 is an enlarged fragmentary detail elevation showing the attaching means for the insulator pin mounting or block.

Figures 4 and 5 are enlarged detail views 35 showing the end attaching members for the insulator pin block.

Figures 6 and 7 are detail views illustrating a modified construction of insulator pin mounting.

Figures 8 and 9 show a detail sectional 40 view, and side elevation, respectively, of a still further modified form of my invention.

Referring more particularly to the drawings, the numeral 2 designates the poles or uprights of the support which are preferably 45 of triangular cross-section, but may be of any desired cross-section. The poles 2 may be secured to anchor bolts as shown at the left of Figure 1, or may be planted directly in a concrete base as shown at the right of 50 Figure 1, as described. A horizontal truss or girder 3 of triangular cross-section is secured between the poles 2. The triangular poles 2 and truss 3 are composed of sixty degree angle chords 4 and ninety degree 55 standard angle lattice 5.

The top chord of the truss member 3 is

terminated short of the base or bottom chords at each end of the truss, so that the bottom chords only are connected to the poles 2 and these connections are made by a 60 single connector so as to provide a flexible connection which will prevent the transference of moments from the poles 2 and truss 3 to each other in the case of the settling of one pole or some other such cause. 65

An insulator pin supporting block 6 is secured in spaced relation above the top chord of the truss 3 by connectors 7, 8, and 9 at substantially the center of the truss.

The connector 7 is bent in substantially 70 an inverted M-shape with its center or apex 10 adapted to rest on the top chord of the truss 3. The sides of the member 7 are cut away to clear the rivet holding the lacing.

The connector 8 is bent in substantially 75 an inverted M-shape with its center or apex 11 adapted to fit over the top chord of the truss and held in place by a rivet or bolt 12.

The center of the block 6 is supported by individual angle supports or connectors 9 80 at each side which are riveted or bolted to lacing members 13.

The top chord of the truss 3 is provided with a bolt or rivet hole 14 between the points of connection of the connector members 7 and 9, so that if desired the block 6 may be shifted to the right by simply changing the center supports 9 to the right side of the lacing members 13 and thus moving the righthand end of the block 6 into position 90 over the apex 15 of the next set of lacing. The connectors 7 and 8 will then be interchanged end for end of the block and the connector 8 secured to the top chord by a bolt or rivet passed through the hole 14, 95 while the connector 7 will be mounted over the apex 15 of the lacing.

An insulator pin 17 having a reduced and threaded shank portion 18 and a flange or shoulder 19 above said shank, is adapted to 100 have its shank portion inserted through a hole or aperture 20 in the block 6 and to be secured in place by a nut 21. Suitable washers or shims 22 are shown between the shoulder 19 and block 6 and the number of shims 105 may be varied to vary the vertical position of the pin 17, while the hole 20 may be changed to any position along the length of the block 6 to vary the transverse position of the pin. 110

The modified form of insulator pin mounting shown in Figures 6 and 7, consists

of a pair of vertical connectors 9^a and a transverse angle support 6^a having a hole 20^a therein to receive the stem or shank 18 of the pin 17. The insulator pin 17 may be adjusted vertically by varying the number of the shims 22 as in the first described form.

The blocks 6 may be composed of wood, either impregnated or plain, or other insulating material.

10 By making the blocks of wood or other insulating material, in case the messenger cable should become loosened from the insulator pin, or the pin should break, the cable will rest on the insulating support and not 15 contact with the metal structure.

While I have shown and described certain specific embodiments of my invention, it will be understood that I do not wish to be limited thereto, since various modifications 20 may be made without departing from the scope of my invention, as defined in the appended claims.

I claim:

1. A support for the overhead system of 25 electric railways comprising the combination with a pair of spaced vertical metal supports and a horizontal metal truss member extending between and secured to said supports, said truss member being of substantially 30 triangular cross-section and having a

single inverted V-shaped top chord of a plurality of connector brackets secured to and projecting above said top chord, and an elongated impregnated wooden insulator block secured to said brackets and extending 35 in a plane parallel with and entirely above said top chord.

2. A support for the overhead system of 40 electric railways comprising the combination with a pair of spaced vertical metal supports and a horizontal metal truss member extending between and secured to said supports, said truss member being of substantially 45 triangular cross-section and having a single inverted V-shaped top chord of a plurality of substantially M-shaped connector brackets having their inverted V-shaped center portions fitted over and secured to said top chord member and having their side portions projecting upwardly materially 50 above said top chord member, said side portions being parallel for at least a portion of their length, and an elongated insulator block secured between the parallel side portions of said connector brackets and extending 55 in a plane parallel with and entirely above said top chord.

In testimony whereof, I have hereunto signed my name.

CHAUNCEY MARSH GOODRICH.
